UNITED STATES PATENT OFFICE.

EDWARD S. T. KENNEDY, OF NEW YORK, N. Y.

MARINE BOILER.

SPECIFICATION forming part of Letters Patent No. 329,912, dated November 10, 1885.

Application filed August 28, 1885. Serial No. 175,516. (No model.)

To all whom it may concern:

Be it known that I, EDWARD S. T. KENNEDY, a citizen of the United States of North America, and a resident of the city, county, 5 and State of New York, have invented a new and useful Improvement in Marine Boilers, of which the following is a specification.

Upright cylindrical boilers and boilers of the "porcupine" type—vertical cylinders 10 with radiating tubes—have great height in proportion to their diameters, and when used as marine boilers in a heavy sea the water line or surface in them is constantly changing from the horizontal to planes of greater or 15 lesser angles thereto, so that the water is often forced up into the boiler steam chamber or dome to such an extent as to enter the steam take-off pipe or pipes and thereby establish a siphon action by which the boiler-water or a 20 considerable portion of it is rapidly drawn off.

The object of my invention is to obviate this objection; and the invention consists in making a central opening in the upper head of the boiler-cylinder, in securing over said 25 opening an upright cylinder closed at the upper end, of same diameter as the opening, which shall communicate with the boiler steam-chamber and extend well up into the smoke-stack, and in fixing in said smaller cylinder 30 one or more elbow pipe or pipes whose vertical leg or legs, open at the top, shall extend nearly to the top of the smaller cylinder to take steam therefrom, and whose horizontal leg or legs, extending through a side or sides 35 of the smaller cylinder or through the wall of the boiler steam-chamber, shall serve for the delivery of the steam.

In order to illustrate my improved device, I show it in the drawings applied to a boiler 40 of the porcupine type.

Figure 1 is a sectional elevation showing my improved device applied to a marine boiler. Fig. 2 is a plan of the same, with hood and smoke-pipe removed.

Reference is to be had to the accompanying 45 drawings, forming part of this specification, in which similar letters of reference indicate corresponding parts in all the figures.

In the drawings, A represents the boiler- 50 inclosing wall or shell; B, the hood, and B' the smoke-pipe. Centrally fixed within the

shell A is the vertical boiler-cylinder C, provided with series of radial tubes a, and D represents the grate-bars. All these parts are those of a boiler in common use, and are not 55 parts of my invention.

I make a central opening, b, in the top of the boiler-cylinder C, and firmly secure over it an upright cylinder, E, of like diameter, communicating internally with the steam-space of the cylinder C, and closed at the upper end. This cylinder E reaches up into the smoke-pipe B', in order to abstract a portion of the heat therein, when the boiler is in operation, for the drying of the steam, and it extends so far upward that no water could be carried from the boiler into its upper portion, however much the water in the boiler might be disturbed by the rolling or pitching of the vessel in a seaway. Within the cylinder E, I 70 fix an elbow steam-take-off pipe, F, which may have a coupling, as shown at d, with the open end of its vertical leg reaching up to near the top of said cylinder E, and with its horizontal leg extending laterally outward, as 75 shown. The upper end of the steam-drying pipe F is so far above the boiler water-line that no ordinary motion of a vessel in a heavy sea could force said water up to it; hence the said pipe could not siphon the water from the 80 boiler.

One or more pipes F may be arranged in the cylinder E, so that the steam could be distributed to several points, and the horizontal portion of said pipe or pipes may be directed 85 out through the smoke-pipe or be carried low enough to be projected out through the hood or the boiler steam-space, as may be most convenient, as shown in dotted lines, Fig. 1.

I am aware of the Patents Nos. 247,910, 90 291,580, and 314,308, and do not claim any construction and arrangement therein shown; but,

Having thus described my invention, I claim as new and desire to secure by Letters Patent— 95

The combination, with inclosing-shell A, hood B, and smoke-pipe B', of a boiler adapted for marine purposes, constructed and arranged substantially as herein shown and described, consisting of an upright central cylinder, C, 100 provided with series of radial tubes a, having in the top of its steam-space an opening over

which is fixed a long upright cylinder, E, closed at the top and extending up into the smoke-pipe B' to near the top thereof, and a steam-drying steam-take-off elbow-pipe, F, fixed within the cylinder E, with its vertical leg reaching nearly to the top of said cylinder and its horizontal leg projecting outward for delivery of steam, as and for the purposes set forth.

In testimony that I claim the foregoing as to my invention I have signed my name, in presence of two witnesses, this 16th day of July, 1885.

EDWARD S. T. KENNEDY.
